MULTIPLEX SIGNALING

Harold H. Beverage, Riverhead, N. Y., assignor to
 Radio Corporation of America, a corporation
 of Delaware

Application March 21, 1933, Serial No. 661,947

12 Claims. (Cl. 178—51)

This invention relates to a method of and system for multiplex signaling. Multiplex systems of various types have been known in the teletypewriter and telephony arts, both radio and wired, heretofore. Some of these systems involve the use of a commutator for time separation of the elements at the transmitter, and a receiver with a similar commutator for separation of the signal elements at the receiver. Systems of this type are in some cases unsatisfactory, due to the difficulty of synchronizing the commutators at the transmitter and at the receiver.

In another type of system the difficulties attending synchronization are overcome by using a commutator for time separation of the signals at the transmitter and modulation frequency separation at the receiver. Any system which depends upon modulating a carrier with a multiplicity of audio frequencies for obtaining different channels has been found by experience to be relatively inefficient, since it is necessary to keep the side band power relatively low as compared with the carrier power. If this is not done, intermodulation or interference between the channels results. A system of this type is sound in theory but in practice is undesirable, due to the fact that the ratio of noise level to signal level is extremely high, and due to the relatively small amount of power available in the sidebands. In tests made by me it was found that the wave modulated with the different frequencies characteristic of the signal elements could only be read through about five percent as much noise as interrupted continuous wave signals where all of the transmitter power was available on a single frequency.

The most efficient multiplexing systems known heretofore involve the use of continuous wave oscillations at the transmitter with a commutator for time separation of the continuous wave, and a receiver with a similar commutator for selecting the signal elements which are received. The commutators at the transmitter and at the receiver are driven by synchronous motors. The motors may be synchronized by a signal impulse sent out from the transmitter. This system is again subject to the disadvantage of synchronizing the motors at the receiver and the transmitter.

The primary object of applicant's invention is to provide a new and novel method of and means for multiplexing signals, which method and means eliminates all, or substantially all, of the material disadvantages noted above.

The above object of applicant's invention is accomplished by a novel multiplexing system in

which time separation of the oscillations into elements characteristic of the signal elements is accomplished at the transmitter by a commutator. The time separation of the oscillations at the transmitter is accompanied by changes in frequency of the continuous wave. The resultant transmitted frequencies are characteristic of the signal elements. The changes in frequency of the continuous waves which accompany the time separation thereof may be accomplished in any manner. Preferably, it is accomplished by the use of a control current, the intensity of which changes in accordance with the signal element to be transmitted. The changes in current intensity control the saturation of a magnetic modulating device, which may be connected in any desirable manner with any stage in the transmitter to accomplish frequency shift of the oscillations thereof.

Any signaling code may be used. Preferably, the Morse cable code is used, and in using the Morse cable code, dots and dashes are of equal length, but are distinguished in transmission and in reception, that is, after demodulation of the high frequency oscillations has been accomplished, by their frequency. For example, the letter "A" might be represented by a dot on 1500 cycles followed by a dot on 1000 cycles, while the letter "B" would be a dot on 1000 cycles followed by three dots on 1500 cycles. In this example, the 1500 cycle dot corresponds to a Morse code dot, while the 1000 cycle dot corresponds to a Morse code dash. No signal corresponds to intervals between elements or between words. Of course, the present invention contemplates the use of three frequencies, one of which represents a dot, the second of which represents a dash, and a third which represents spaces or intervals.

In the above example it is assumed that one channel only is being used. The present invention, which relates to multiplexing, contemplates the use of 2, 3, or more, channels. Furthermore, each channel may use two frequencies and no signal for spacing, or two frequencies for marking and a third frequency for spacing. In the prior example, four frequencies will be necessary for two channels since no current for intervals and spacing suffices for both channels. If an interval or spacing frequency is used then five frequencies will be necessary, the additional spacing or interval frequency sufficing for both channels.

Where three channels are used six frequencies, with no signal for intervals and spacing, may be

used, or seven frequencies where a distinct frequency is used for spacing and intervals.

Signaling speed is increased by coordinating the commutators for the time separation of the continuous wave and the automatic keyers for keying the transmitter by way of the magnetic modulator so that the spacing intervals on one channel are utilized for marking intervals on other channels and vice versa. This coordination of the time separation commutator with the automatic keyers increases the speed of keying in a manner analogous to the manner in which the speed of keying is increased by the invention disclosed in Briggs' Patent No. 1,781,361.

15 The magnetic modulator, the saturation of the core of which is varied by currents of different intensity, is of a type to accomplish linear frequency shift in the continuous waves. The transmitter itself is of the type in which the carrier 20 is radiated at maximum power at all times, and signaling on the different channels is made selective by taking into account the amount by which the carrier is shifted in frequency by the various signaling elements.

25 The time separated frequency shifted signals may be received on a crystal controlled radio frequency receiver. The crystal may be adjusted to match the frequency of the transmitter so that by using heterodyne reception the local oscillator beats the received signal to obtain a beat 30 note which is zero or substantially zero during intervals or spacing periods when no signals are being transmitted on either channel.

The heterodyne receiver feeds into a high pass 35 filter circuit which may include the necessary amplifiers. The high pass filter circuit supplies the frequency, if any, to a plurality of filter circuits, there being a filter circuit for each different frequency transmitted. The filter circuits 40 completely separate and isolate the resulting beat notes. The filter circuits may be connected with rectifiers and by way of said rectifiers to recording devices.

Numerous other novel features, in addition to 45 those outlined briefly above, will appear from the following detailed description of my novel method of and means for multiplexing signals, and therefrom when read in connection with the drawings in which:

50 Figure 1 illustrates diagrammatically the manner in which time separation of the oscillations is accomplished and the manner in which currents of different intensity are supplied to the magnetic modulator, which may be connected to any suitable transmitter, and shows also the relation of the marking impulses on the individual channels and the resultant frequency shift envelope resulting from the coordination of two channels;

60 Figure 2 shows diagrammatically the essential elements of my multiplexing system at the transmitting end; and Figure 2a illustrates in box form the manner in which the transmitters AT #1 and AT #2 are controlled by a tape in which 65 the signal characters to be transmitted are punched.

Figure 3 illustrates diagrammatically a receiver of the heterodyne type which feeds the beat notes through a high pass filter to the frequency separation circuit and from thence to the recorders;

70 Figure 4 illustrates the characteristics of the band pass filters shown schematically in Figure 3;

75 Figure 5 is the same as Figure 1, except that in

Figure 5 signaling on three channels by the use of six frequencies is accomplished; while

Figure 6 is similar to Figure 2, except that it shows a multiplexing system in which signals may be sent out on three channels.

80 The method of multiplexing signals in accordance with my invention will be understood by reference to Figure 1 of the drawings. The squares designated by the numerals 1 and 2 represent commutator segments. The shaded 10 squares, which are marked No. 1, are all connected together and to a slip ring shown schematically at SR₁. In like manner, all of the No. 2 squares, or commutator segments, are connected together to a second slip ring, shown schematically at SR₂. A single brush 1 bears on the commutator so that when the commutator is rotated the brush 1 makes contact with the segments 1 and 2 alternately. The magnetic modulator MM has its saturating winding 6 connected 20 with the brush 1, with a source of potential 9, and by way of a plurality of resistances R₁, R₂, R₃ and R₄ to a plurality of contacts K₁, K₂, K₃ and K₄. Closing of the contacts completes the circuit of the magnetic modulator winding 6 25 through the battery by way of one of the segments 1 or 2 and the slip rings SR₁ or SR₂. As the commutator revolves it connects the transmitter alternately to the two channels by way of the contacts K₁, K₂, K₃ and K₄. The frequency 30 of the transmitter T, which is connected by way of the winding 10, with the magnetic modulator, is controlled by the current flowing through the commutator segments under the brush 1 at that particular instant, that is, when that particular 35 contact is closed.

The resistances R₁, R₂, R₃ and R₄ are all of different value so that currents of different intensities flow through the winding 6 of the magnetic modulator. Each slip ring is associated 40 with a channel and the current is adjusted to four different values for two channels. This is accomplished by adjusting the resistances R₁, R₂, R₃ and R₄ connected with the keys K₁, K₂, K₃ and K₄ of the keying relays. For purposes of illustration, I have assumed that when K₁ is closed a current I₁ will flow in channel 2 and this current will represent a dash; current of intensity I₂ will flow in channel 2 when K₄ is closed and this will represent a dot; current of intensity I₃ will flow in channel 1 when K₃ is closed and this will represent a dot; current of intensity I₄ will flow in channel 1 when K₂ is closed and this will represent a dash; while, current of zero intensity will flow when spaces or intervals appear in the signal. The keying relays may be 50 separably, biased polar relays, such that a positive line current operates one relay while a negative line current operates the other. With no line current the bias will pull both relays to the "off" side so that no current will flow to the commutator during the idle time on that channel. These keying relays may be modified in a number of ways, such as using a zero center relay, tube relays, etc. It is also possible to put a fixed 55 current on the modulator and key straight from the line with positive and negative impulses. A preferred form of relay has been shown in Figure 2, which will be discussed in detail hereinafter.

A positive impulse corresponds to a dot, and a negative impulse corresponds to a dash in the Morse cable code. The currents I₁, I₂, I₃ and I₄, referred to above as flowing in the circuits when the contacts K₁, K₂, K₃ and K₄ close, represent the currents flowing in the commutator segment 75

corresponding to the characters represented. The little sketch at the bottom of Figure 1 represents the relation between these control currents and the transmitter frequency. With this in mind it is easy to draw out the combined frequency envelopes of the transmitter, as shown. The frequency envelope of the combined channels, that is, channels 1 and 2, has been shown in line 1. The envelope of the control current sent out over channel No. 1 has been shown separately in line 2 and the envelope of the control current sent out over channel No. 2 has been shown separately in line 3. These envelopes will be referred to again hereinafter. The manner in which magnetic modulation is accomplished and the nature of the receiver will be described first.

Referring to Figure 2, the commutator having the segments 1, 2 on its periphery may be mounted on a shaft S rotating in a bearing 12. The shaft S may be driven by a motor 14 at the desired speed. Slip rings SR₁ and SR₂ for channels 1 and 2 may be fastened to a face of the commutator for rotation therewith. Brushes B₁ and B₂ may cooperate with the slip rings to complete circuits by way of magnetic relays MR₁ and MR₂ with automatic keying devices AT₁ and AT₂. The automatic keying devices are driven in synchronism with the commutator by way of bevelled gears 14' and 14'' by the motor 14, as shown. The Wheatstone transmitters AT₁ and AT₂ may be of the automatic type and are driven in synchronism at the same rate of speed through the gears 14' and 14''. The connection between the automatic transmitters AT₁ and AT₂ and the gearing 14' and 14'' respectively on the shaft 15 is such that the spacing intervals of one transmitter coincide with the marking intervals of the other transmitter, and vice versa, that is, the plunger contacts of automatic transmitter AT₁ for channel 1 are always up when the plungers on the automatic transmitter AT₂ for channel 2 are down, and vice versa. The automatic transmitters AT₁ and AT₂ are connected by wires 16, 18 and 20, 22 respectively with relay windings 17, 19 and 21, 23 respectively of magnetic relays MR₁ and MR₂ respectively. The contacts K₃ and K₄ are closed under certain conditions by the armatures associated with magnetic relay windings 17 and 19 respectively. The contacts K₄ and K₁ are closed under certain conditions by current in the windings 21 and 23 respectively of magnetic relay MR₂. The armatures of the windings 17, 19, 21 and 23 are connected by way of resistances R₃, R₂, R₄ and R₁ respectively to the source of potential 9, which is in turn connected with the winding 6 of the magnetic modulator MM. The winding 6 is connected with the brush 7 bearing on the periphery of the commutator. The automatic transmitters are coordinated to each other so that one is marking when the other is "off", and vice versa. The operating time is divided up equally between each transmitter. This necessitates the use of signal elements of like time duration. Both transmitters are coordinated with the commutator so that a segment 1 is under the brush 7 when the automatic transmitter AT₁ is marking and a segment 2 is under the brush 7 when the automatic transmitter AT₂ is marking. Thus the time of operation is divided up equally between the two channels. The current flowing in the winding 6 varies the intensity of the flux in the core of the magnetic modulator. This in turn varies the permeability of the iron core which causes the induc-

tance of winding 10 to vary in accordance with the current variations. The winding 10 is shunted across a portion of the inductance 27, which, in conjunction with the condenser 29, determines the frequency of oscillation of vacuum tube 31. When current flows in winding 6 the inductance of winding 10 decreases. This decreases the total inductance in the oscillating circuit and causes vacuum tube 31 to oscillate at a higher frequency. The amount of frequency shift is governed by the value of the control current in the winding 6. Choke coils 37 and 39 are inserted in series with control winding 6 to keep radio frequency from flowing in the control circuit.

As an example to further illustrate the operation of this circuit, assume that with no control current flowing in winding 6 of the frequency shifting device MM the transmitter sends out a frequency of 10,000,000 cycles, and that the oscillator associated with the receiver at the other end of the circuit is also adjusted to 10,000,000 cycles, so that the beat note is substantially zero. Now assume that the intensity of the current flowing in resistance R₄ is such as to decrease the inductance of MM to such an extent that the transmitter frequency is increased to 10,000,000 cycles. At the receiver the transmitter frequency beats with the local oscillations, which results in a beat of 2000 cycles; the resistance R₃ permits a current to flow through the winding 6, which decreases the frequency of the oscillations transmitted sufficiently to result in a beat note of 1500 cycles when the transmitted oscillation beats with the local oscillations at the receiver; the resistance R₂ permits sufficient current to flow through the winding 6 to lower the transmitted frequency to such a value that a beat note of 1000 cycles results at the receiver; while, the resistance R₁ allows sufficient current to flow through the winding 6 to produce a beat note at the receiver of 500 cycles. Thus, the letter "A" on channel 1 might be represented by a dot on 1500 cycles (Morse dot) followed by a dot on 1000 cycles (Morse dash); while, the letter "B" might be represented by a dot on 1000 cycles followed by three dots on 1500 cycles. Of course, where two channels are used the elements of one letter on one channel should be alternated with elements of another letter on the other channel, as illustrated in line 1 of Figure 1. The frequency modulated oscillations may be amplified by power amplifier 25 and radiated or utilized in any desired manner.

While I have described one means for shifting the frequency of the transmitter, many methods are known to the art, and any of them could readily be adapted for use with my invention.

At the receiver, see Figure 3, the signals are picked up on an antenna system 40 and supplied to a radio frequency amplifier 42 followed by a detector 44 with associated oscillator 46. The audio frequencies are amplified in amplifier 48. Oscillations of a frequency substantially equal to the frequency of the incoming signal are supplied from oscillator 46. The oscillator 46 is preferably of the crystal controlled type, so that the frequency supplied at the receiver matches the frequency of the transmitter and a zero or substantially zero beat note results when none of the channels are marking. This beat note, if any, may be further amplified in 48 after passing through high pass filter 50. This high pass filter blocks out beat notes below a certain frequency and passes beat notes between this frequency and an upper limiting frequency. The purpose of

this high pass filter is to eliminate harmonics which might be of such frequency as to pass through one or more of the band pass filters. The beat notes resulting are supplied to the filter circuits 52, 54, 56 and 58 and from thence by way of rectifiers 60, 62, 64, and 66 to the recorder coils 68 and 82.

At the receiver the transmitter comes in at or near zero beat when both channels are off. This low frequency beat note is cut off by the high pass filter 50 so that nothing is heard. As soon as the brush 7 touches segments No. 1 on the commutator, the transmitter is keyed to a frequency F_3 , see line 1 of Figure 1. A beat note of frequency $F_3 - F_0$, or 1500 cycles, in this case, is in the output of the receiver and may be heard. This beat note is passed through the filter 52 and by way of the rectifier 60 to the coil 68 of recorder No. 1 where it pulls up the pen 74. When the segment 20 No. 2 reaches the brush 7 the beat note instantly changes to $F_1 - F_0$, or 500 cycles. This pulls down the pen 88 on recorder 2. Simultaneously the pen of recorder 1 has dropped back to zero since the frequency F_3 has disappeared. When the third 25 segments, that is, the second segment No. 1, reaches the brush 7 the frequency F_2 appears since contact K_2 has been closed by the automatic transmitter AT_1 . This beat note $F_2 - F_0$, which is equal to 1000 cycles, passes through filter 54 of channel No. 1 and pulls down the recording pen of recorder 1 to complete the letter "A" on channel 1 in its original form, as shown in lines 1 and 2 of Figure 1. In this manner the letter "B" is keyed by the automatic transmitter AT_1 on channel 1, 30 while automatic transmitter AT_2 is completing the letter X and starting on letter Y over channel 2, as shown in Figure 1. The receiver has four band pass filters corresponding to the four frequencies necessary for two channels when no signal or zero beat is used for spacing.

The characteristics of the band pass filters which were illustrated diagrammatically in Figure 3, have been shown in Figure 4. The high pass filter eliminates all beat notes below about 200 45 cycles and thereby overcomes any difficulties that might be encountered from harmonics of the spacing frequency. For example, if the spacing frequency should overload the audio amplifier, harmonics would be generated which might pass 50 through the band pass filters and produce false marking on the recorders. By placing the high pass filter 50 (Figure 3) ahead of the audio amplifier, this difficulty is eliminated.

The four filters are centered at 500, 1000, 1500, and 2000 cycles, and are made as wide as possible in order to allow some drift between the transmitter frequency and the local oscillator frequency at the receiver. The signals may be kept centered in the filters by slight adjustment of the oscillator at the receiver.

When it is desired to transmit on three channels the commutator may be as illustrated in Figure 5. Here, the segments run in sequence, 1 to 3 and repeated. Three slip rings are necessary and three automatic transmitters of the type similar to the two shown in Figure 2 will be necessary. In view of the fact that the system in which three channels are used will be clearly understood from the prior description of the system, in which two channels have been used, it is thought unnecessary to describe in detail the system in which multiplexing on three channels is accomplished. The system has, however, been 70 illustrated in Figure 6.

In Figure 6 parts which correspond to the similar parts in Figure 2 have been designated by like reference symbols.

In Figure 2 the automatic transmitters may be considered as spaced 180 degrees apart so that 5 when one is marking the other is spacing, and vice versa. In the three channel system of Figure 6 the automatic transmitters are spaced by the gearing 14', 14'' and 14''', 120 degrees apart so that when one is marking the others are 10 spacing.

In drawing the envelopes of the frequencies sent out by the transmitter over the three channels, in Figure 5, the "off" signal has been placed intermediate the three signaling frequencies for 15 convenience and to facilitate understanding of the invention.

In some cases it is desirable to interrupt or cut off the carrier frequency oscillations when spacing occurs on all channels. This may be accomplished as indicated in Figures 2 and 6. When all channels happen to be spacing the control current in winding 6 of modulator MM falls to zero because all of the circuits in series with the modulator are interrupted. Relay 41 is adjusted 25 so that the minimum current I_1 , that is, the minimum current which produces a signaling frequency, will hold the relay closed, thereby putting normal bias on oscillator grid 51 through relay contact 47 from battery 45. As soon as the control current drops to zero (when all channels are spacing) relay contact 47 is pulled over by a spring S and puts a high negative bias from batteries 45 and 43 in series on the grid 51 of oscillator 31. This negative bias interrupts the oscillations being generated by said tube so that no radiation takes place during intervals on all channels.

While the oscillation interrupting means has been shown connected with the oscillation generator, it will be understood that this interrupting means may also be connected with any stage subsequent to the oscillation generator. For example, it may be connected with any succeeding amplifier, frequency multiplier, or other relaying 45 stage included in the circuit between the oscillation generator and the radiating system.

Having thus described my invention and the operation thereof, what I claim is:

1. In a multiplex telegraph system, the method 50 of communication by means of three element signals which comprises generating high frequency oscillations, producing discrete current impulses of different intensities characteristic of the signal elements to be transmitted over each channel, and producing changes in the frequency of the oscillations which are determined by the changes in intensity of said current impulses, at least two different frequencies being transmitted over each channel. 60

2. The method of multiplexing signals over a plurality of channels which includes the steps of producing current impulses of constant duration and intensity which are characteristic of signal elements, and producing high frequency oscillations, the frequencies of which are determined by the intensity of said current impulses, there being at least two different frequencies for each channel, which frequencies differ from the frequencies use for the other channels. 70

3. The method of multiplexing signals over two channels which comprises producing two current impulses of like duration but of different intensities characteristic of the elements of the signal to be transmitted on one of said channels, pro- 75

ducing two other similar current impulses of still other intensities for said other channel, and generating oscillations whose frequency is determined by the intensity of the current impulses.

5 4. The method of multiplexing signals which includes the steps of producing signal impulses of a predetermined intensity, producing signal impulses of a different intensity, said first and second named impulses representing the marking 10 elements in Morse code signaling, the absence of a current impulse being characteristic of spacing in the Morse code signaling, and producing oscillations, the frequency of which varies substantially in accordance with the intensity of the impulses.

15 5. The method of multiplexing signals which includes signaling on a plurality of channels simultaneously by producing current impulses, the intensities of which are characteristic of the signal 20 elements to be transmitted, there being an impulse of different intensity for each channel and for each signal element on each channel, producing high frequency oscillations characteristic 25 of the intensity of each signal impulse, and coordinating said impulses so that the spacing intervals on one channel are utilized for marking intervals on another channel and vice versa.

6. The combination of an oscillation generator 30 including an electron discharge device having its electrodes coupled by way of a frequency determining circuit including, an inductance, and means for keying the oscillations produced by varying the value of said inductance, of a winding coupled to said inductance, a second winding 35 magnetically related to said first named winding, a commutator, a plurality of groups of segments on said commutator, a brush bearing on said commutator segments, said brush being connected to one terminal of said last named winding, slip 40 rings on said commutator, there being a slip ring for each group of segments, a brush bearing on each of said slip rings, normally open contacts connected with each of said last named brushes, a resistance connecting each of said contacts by 45 way of a common source of potential to the other terminal of said last named winding, magnetic relays associated with said contacts, and automatic keying means in circuit with the magnetic relays, there being a keying means for each group 50 of segments, and a motor for driving said commutator and said keying means in synchronism.

7. Multiplex receiving means comprising, a receiver responsive to a band of frequencies, heterodyne demodulating means coupled to said receiver, a high pass filter coupled to said demodu-

lating means, a plurality of pairs of band pass filters connected with said high pass filter, and a single recording means connected to each pair of band pass filters.

8. Signaling means comprising an electron discharge device having anode, cathode, and control grid electrodes, a reactance coupling said anode, cathode and control grid for producing sustained oscillations and for determining the frequency of the same, electrical means for controlling the effective value of said reactance for varying the frequency of the oscillations produced over a predetermined range, and means in circuit with said electrical means for applying a potential to said control grid electrode to render said device 15 inoperative.

9. The method of multiplexing which includes the steps of producing oscillations, interrupting said oscillations to produce impulses of high frequency oscillatory energy, and simultaneously 20 changing the frequency of the time separated oscillations.

10. The method of multiplexing by means of high frequency oscillations, the frequency of which is varied through a plurality of steps to 25 signal on a plurality of channels, which includes the steps of coordinating said channels so that marking intervals on one channel utilize the spacing intervals on another channel, and interrupting said oscillations when spacing intervals 30 appear simultaneously on all channels.

11. A device for multiplexing signals comprising a transmitter, a modulator connected therewith, a plurality of sources of impulses of different intensity, there being employed a plurality 35 of impulses of different intensity for each channel, and automatic means responsive to signal characters for selectively associating said sources with said modulator.

12. A multiplex telegraph receiver for receiving 40 a plurality of frequencies each of which is characteristic of a signal impulse element to be transmitted which comprises an energy collector, heterodyne demodulating means coupled to said collector, a filter coupled to the output of said 45 demodulating means, and a plurality of additional filters in circuit with said first filter, each of said plurality of filters being individual to one of the signal impulse elements to be received, at least two filters being provided for each channel and 50 a translating device for each channel which is responsive to the signal impulses received over the filters in said channel.
